Robert H. Hill, Elgin, Ill., assignor to J. E. Taylor, doing business as Taylor Engineering Company, Elgin, Ill.

Application May 29, 1936, Serial No. 82,503

10 Claims. (Cl. 62—121)

This invention relates to presses and more particularly to presses for compacting into solid blocks carbon dioxide solidified upon expansion of liquid carbon dioxide.

5 A snowlike solid is produced upon expansion of liquid carbon dioxide but in this form it is not suitable for most commercial and other usages wherefore this snowlike solid is compacted into solid blocks, and such solid blocks are often 10 divided into smaller blocks to facilitate handling and usage of solidified carbon dioxide.

Heretofore it has been difficult to compact snowlike solidified carbon dioxide into uniform blocks because of, among other things, the 15 structural characteristics of the chamber wherein the snowlike solid was compacted, the entrapment of gases in the chamber, the difficulty entailed in properly distributing the compacting pressure and the like. Therefore the primary 20 object of my invention is to compact snowlike solidified carbon dioxide into solid uniform blocks.

Other important objects are to prevent entrapment of gases during compacting of solidified carbon dioxide; to collect the snowlike solidified carbon dioxide in the chamber in which the liquid carbon dioxide is expanded and to compact the snowlike solidified carbon dioxide in such chamber; to prevent escape of carbon dioxide gas during expansion of liquid carbon dioxide; 30 and to open the chamber to the atmosphere during compacting of the snowlike solidified carbon dioxide.

Still further objects are to insure proper distribution of the applied pressure during the compacting of snowlike solidified carbon dioxide; to facilitate extraction of the solid blocks produced by compacting snowlike solidified carbon dioxide; to open a gas escapement valve upon closure of the chamber in which liquid carbon dioxide 40 is expanded and to close such valve prior to the compacting of the snowlike solidified carbon dioxide collected in the chamber when liquid carbon dioxide is expanded therein; and to provide a novel apparatus of simple and economical construction and efficient and positive operation for collecting and compacting snowlike solidified carbon dioxide.

A selected embodiment of my invention is illustrated in the accompanying drawing wherein

50 Fig. 1 is a side elevational view;

Fig. 2 is a fragmentary vertical sectional view taken substantially on the line 2—2 on Fig. 1 and showing certain of the elements in one of the operative positions thereof;

55 Fig. 3 is a view similar to Fig. 2 and showing certain of the elements in still another operative position;

Fig. 4 is a transverse sectional view taken substantially on the line 4—4 on Fig. 3; and

60 Fig. 5 is a top plan view.

In the form of my novel apparatus illustrated in the accompanying drawing I provide a pair of square tie plates 6 and 7. A sleeve as 8 extends between corresponding corners of the tie plates and a belt as 9 is passed therethrough whereby nuts as 10 may be tightened down onto the tie plates to thereby securely clamp the tie plates against the ends of the sleeves 8. An arrangement such as this is provided at each corner of the tie plates whereby the tie plates are securely connected together.

A medially located square opening 11 is provided in the plate 6 and a square cylinder 12 has the lower end rested on the upper surface of the plate 6 about the opening 11 whereby the opening 15 in the cylinder 12 is aligned with the opening 11. A head 13 rests on the upper end of the cylinder 12 and closes the opening therein. The head 13 is clamped against the cylinder 12 and the cylinder 12 is in turn clamped against the plate 6 20 by tie rods as 14.

A manually operated inlet valve 15 is mounted in the head 13 and a supply pipe 16 is connected thereto. An outlet valve 17 is also mounted in the head 13 and includes a plunger 18. One end of a lever 19 bears on the outer free end of the plunger 18. The upper end of a push rod 20 is engageable with the other end of the lever 19. The push rod 20 is passed through aligned openings 21 and 22 respectively provided in the head 13 and tie plate 6 whereby the lower end of said push rod is extended below the tie plate 6. A collar 23 on the push rod 20 limits the extent thereof below said tie plate 6, this collar engaging the upper surface of the head 13. An outlet 30 pipe 24 leads from the outlet valve 17.

A liner L is provided for the opening in the cylinder 12 and the opening 11. The inner surfaces of the liner L are tapered in a manner and for a purpose explained more fully hereinafter. 40 The liner L in cooperation with the head 13 and with elements explained more fully hereinafter provides a chamber C and the valves 15 and 17 open into the upper end of this chamber.

A medially located, cylindrical opening 25 is 45 provided in the tie plate 7 through which a piston 26 is extended. A follower 27 is secured to the lower end of the piston 26 and rides on the walls of a cylinder 28, the upper end of which is fitted in a groove 29 in the lower face of the tie plate 7 in spaced relation with the opening 25. 50 A head 30 is provided in the lower end of the cylinder 28 and this head is clamped against the cylinder, and the cylinder is clamped against the tie plate 7 by tie rods 31 extended between said head and tie plate. A supply pipe 32 opens into the cylinder 28 through the head 30 below the follower 27 and has a valve 33 therein for controlling flow therethrough. Another supply pipe 34 also having a valve (not shown) therein opens 55 60

into the cylinder 28 near the top thereof to admit fluid into the cylinder 28 about the piston 26 and above the follower 27, suitable packing generally indicated by 35 being provided about the piston 26 in the opening 25 to prevent escape-
 5 ment past the piston of fluid admitted into the chamber 28 above the follower 27. Rings 36 or other packing means are provided on the periphery of the follower 27 to prevent leakage thereby.
 10 A piston head 37 is provided at the top of the piston 26. This piston head 37 is shaped complementary to the liner L but the faces of the head 37 are adapted to be spaced from the adjacent faces of the liner L even when the piston head 37 is moved up into the chamber C, the taper on said liner being such that the chamber is smaller at its upper end than at its lower end through which the piston head 37 enters said chamber. A sealing head generally indicated by
 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580

A collar 44 is provided on the piston 26 immediately below the piston head 37 and shoulders as 45 are provided on the outer faces of this collar 44. Pockets as 46 are provided in the head 38 and latch dogs as 47 are slidably mounted in the pockets 46. Springs as 48 extend into bores in the latch dogs 47 and engage heads as 49 and these springs force the latch dogs 47 into engagement with the shoulders 45 whereby the head 38 is latched to the piston 26.

Pockets as 50 extend into the head 38 from the lower surface thereof and buffer springs 51 are mounted in these pockets and extend beyond the lower face of the head 38. Packing, generally indicated by 52, is provided in the opening 41 about the piston 26 to prevent leakage past the piston.

As best illustrated in Fig. 4, foraminated discs 53 and 54 are provided in the lower wall of the head 38, said discs and the valves 15 and 17 being disposed in said head 38 to open into the chamber C. The foraminated discs 53 and 54 close open ends of a passage 55 that extends transversely across the head 38. A valve 56 opens into the passage 55 and a supply pipe 57 leads to this valve from a source of fluid under high pressure.

Normally the follower 27 is positioned near the bottom of the cylinder 28 and the head 38 is latched to the piston 26 and the buffer springs 51 rest on the upper surface of the tie plate 6, the elements being shown in this position in Fig. 1. When, however, the valve 33 is opened and fluid under high pressure is admitted into the cylinder 28 below the follower 27, said follower and therefore the piston 26 is forced upwardly through the cylinder 28. The pipe 33 leads to a source of liquid under high pressure

and the follower 27 and cylinder 28 provide an hydraulic press.

At the initiation of an operation liquid at a predetermined pressure is admitted into the cylinder 28 below the follower 27 to cause the follower 27 and piston 26 to rise, and this liquid is admitted until the head 38 is in clamping relation with the lower surface of the tie plate 6 whereupon admission of further liquid into the cylinder 28 is interrupted but the predetermined pressure is maintained on the liquid which has been admitted into the cylinder. At the end of this phase of the operation the elements are disposed as shown in Fig. 2 and when in this position the gaskets 29 and 43 afford a gas-tight seal at the lower end of the chamber C.

The lower end of the push rod 20 is normally disposed in the position shown in Fig. 1 and therefore just prior to the time the head 38 attains the position shown in Fig. 2 said head 20 engages the push rod 20 which is therefore forced upwardly and acts on the lever 19 to so pivot the lever that the plunger 18 of the valve 17 is forced downwardly wherefore the valve 17 is opened.

The pipe 16 leads to a source of liquid carbon dioxide. Thus, when the parts are positioned, as just described, the valve 18 is opened and liquid carbon dioxide at proper pressure flows into the chamber C where it expands. Part of the expanded carbon dioxide solidifies and is collected in the chamber C. That part of the carbon dioxide which does not solidify passes out of the chamber through the open valve 17 as a gas and flows through the pipe 24 to suitable gas collecting means. The valve 15 is permitted to remain open until a predetermined quantity of snowlike solidified carbon dioxide is collected in the chamber C above the piston head 37, and when the desired amount of solidified carbon dioxide has been collected the valve 15 is closed.

Then the pressure of liquid admitted through the pipe 32 is raised above the predetermined pressure which has maintained the head 38 in sealing position and additional liquid is admitted into the cylinder 28 whereupon the follower 27 and piston 26 are forced up into the chamber C. The springs 48 which maintain the latch dogs 47 in engagement with the shoulders 45 exert sufficient pressure on the latch dogs to prevent disengagement of the latch dogs from the shoulders 45 by the aforesaid predetermined pressure. When, however, the liquid pressure is raised and the follower 27 is forced upwardly to cause the piston head 37 to rise in the chamber C, the pressure exerted by the springs 48 is overcome whereupon the shoulders 45 move from engagement with the latch dogs 47 and the head 38 is unlatched from the piston 26. The head then descends into its initial position, the buffer springs 51 absorbing the shock incident to the descent of the head 38. Suitable means may be provided to force the head to descend but preferably the weight of said head is sufficient to cause it to descend when it is unlatched from the piston 26.

When the head 38 is thus unlatched and descends into its normal position, as in Figs. 1 and 3, the push rod 20, being no longer held in raised position by the head 38, also descends into its normal position, as in Fig. 1, whereupon the valve 17 is closed by its spring.

As soon as the head 38 descends, the gasket 39 disengages the lower surface of the tie plate 6 and the gasket 43 disengages the edges 42. Hence since the faces of the head 37 are spaced

from the adjacent faces of the liner L, an outlet to the atmosphere is afforded past the faces of said head whereby as said head 37 ascends in the chamber C and presses the snowlike solidified 5 carbon dioxide into the solid block against the head 13 any gas remaining in the chamber C escapes to the atmosphere past said head 37.

Inasmuch as the liner L is so tapered that the chamber C is larger adjacent the head 37 than at the other end thereof, the pressure impressed by the head 37 on the carbon dioxide causes the solidified carbon dioxide to be firmly compacted especially at the smaller end thereof adjacent the head 13 and therefore compacting of the snowlike solidified carbon dioxide into a solid 15 uniform block is insured.

The taper of the liner L also facilitates removal of the solid block into which the snowlike solidified carbon dioxide is compacted by the 20 ascent of the head 37 for after the head has been moved into a position like that shown in Fig. 3, which results in compacting the solidified carbon dioxide into a solid uniform block, the application of further pressure through the pipe 32 into the cylinder 28 is interrupted and means controlling flow through the pipe 34 are opened whereby fluid pressure is applied on the upper 25 side of the follower 27 which thereupon starts to descend and therefore the head 37 starts to descend. At this time the valve 56 is opened whereupon fluid at high pressure, such as air or carbon dioxide, is admitted into the passage 55, and this high pressure fluid passes through the 30 foraminated discs 53 and 54 wherefore pressure is applied to the upper side of the block of compacted solidified carbon dioxide, and this pressure is sufficient, in cooperation with the taper of the liner L, to loosen the block from the liner and therefore the block descends with the head 37 which is returned to the position shown in Fig. 1. When the head 37 attains the position shown in Fig. 1 the block of compacted solidified carbon 40 dioxide may be removed therefrom between the bolts 8. At this time the elements will have been returned to the position shown in Fig. 1 and the 45 above described operation may be repeated.

It will be manifest from the foregoing description that I have provided a press including a chamber wherein carbon dioxide may be expanded to thereby afford a supply of snowlike solidified carbon dioxide. Any of the carbon dioxide which does not convert into a solid may be withdrawn so as to prevent collection thereof in the chamber in which the expansion is effected. I have so arranged the press that the expansion may be carried out in a gas-tight chamber and also so that when a desired amount of solidified carbon dioxide has been collected in the chamber, the chamber may be opened to the atmosphere so that when pressure is applied to compact the snowlike solidified carbon dioxide into a solid block any gas remaining in the chamber may escape freely.

I have so shaped the chamber that the compacting pressure will be so distributed that the snowlike solidified carbon dioxide will be compacted into a uniform solid block and furthermore the shape of this chamber is such that removal of the solid block from the chamber is facilitated. The taper of the chamber wall need not be extended throughout the extent thereof but may be confined to the part thereof where the capacity is effected. Moreover, the solid block passes from the chamber on the means which ap-

ply the pressure thereto whereby removal of the block from the chamber is further facilitated.

It will be apparent that I am enabled to accomplish the foregoing by providing a head and enabling this head to be latched to the pressure 5 applying means in such a way that upon the application of a certain pressure the head and piston will be latched together and afford a gas-tight closure for the chamber, but the arrangement is such that upon the application of a higher pressure the pressing means may be detached from the head to thereby open the chamber to the atmosphere.

Thus while I have illustrated and described a preferred form of my invention it is to be understood that this is capable of variation and modification and I therefore do not wish to be limited to the precise details set forth but desire to avail myself of such changes and alterations as fall within the scope of the following claims.

I claim:

1. Apparatus of the character described, including a chamber having a normally open end, means for supplying a volatile fluid to the chamber for expansion therein to afford an accumulation of solid in the chamber, movable means for closing the normally open end of said chamber and for compressing the solid accumulated in the chamber into a compact form, and means for operating said movable means to seal the normally open end of said chamber during accumulation of the solid in said chamber and to subsequently unseal the normally open end of said chamber and compress the accumulated solid, the unsealing of the normally open end of said chamber permitting any unsolidified gas remaining in the chamber to pass therefrom through the said normally open end of the same during the compressing of the accumulated solid into compact form.

2. Apparatus of the character described, including a chamber having a normally open end, means for supplying a volatile liquid to the chamber for expansion therein to afford an accumulation of solid in the chamber, movable means including separable parts for closing the normally open end of said chamber and for compressing the solid accumulated in the chamber into a compact form, and means for operating said movable means to position said parts so as to close the normally open end of said chamber during accumulation of solid therein and to subsequently effect separation of said parts so as to unseal the normally open end of said chamber and compress the accumulated solid, the unsealing of the normally open end of said chamber permitting any unsolidified gas remaining in the chamber to pass therefrom through the said normally open end of the same during the compressing of the accumulated solid into compact form.

3. Apparatus of the character described, including a chamber having a normally open end, means for supplying a volatile fluid to the chamber for expansion therein to afford an accumulation of solid in the chamber, movable means including separable parts for closing the normally open end of said chamber and for compressing the solid accumulated in the chamber into a compact form, means for latching the separable parts of said movable means together, and means for moving the latched separable parts as a unit into position to close the normally open end of said chamber during the accumulation of the solid therein and to subsequently move one of

said parts relative to the other whereby the latching means is released and said parts are separated to thereby unseal the normally open end of said chamber and compress the accumulated solid, the unsealing of the normally open end of said chamber permitting any unsolidified gas remaining in the chamber to pass therefrom through said normally open end during the compressing of the accumulated solid into compact form.

4. Apparatus of the character described, including a chamber having a normally open end, means for supplying a volatile liquid to the chamber for expansion therein to afford an accumulation of solid in the chamber, movable means including separable parts for closing the normally open end of said chamber and for compressing the solid accumulated in the chamber into a compact form, and pressure operated means for moving the separable parts of said movable means, said pressure operated means moving said separable parts as a unit upon the application of a predetermined pressure into position to close the normally open end of said chamber during the accumulation of solid therein, said pressure operated means moving one of said parts relative to the other upon the application of a pressure higher than the predetermined pressure to thereby unseal the normally open end of said chamber and compress the accumulated solid, the unsealing of the normally open end of said chamber permitting any unsolidified gas remaining in the chamber to pass therefrom through said normally open end during the compressing of the accumulated solid into compact form.

5. In a device of the character described, the combination of a chamber having a closed end and a normally open end, means for supplying a volatile fluid to the chamber for expansion therein to afford an accumulation of solid in the chamber, and a piston movable through said chamber from the normally open end thereof toward the closed end of the same to compress the solid accumulated in the chamber at the closed end thereof, said chamber being larger in diameter at the normally open end thereof than at the closed end of the same so that the compressed solid may be withdrawn from the said chamber by way of the said larger end thereof after the operation of compressing the same.

6. Apparatus of the character described, including a chamber having a closed end and a normally open end, said chamber having the wall thereof tapered whereby the chamber is smaller at the closed end than at the open end thereof, means for supplying a volatile fluid to the chamber for expansion therein to afford an accumulation of solid in the chamber, and a piston movable through said chamber from the normally open end thereof toward the closed end of the same to compress the solid accumulated in the chamber at the smaller end thereof, said piston being spaced from the wall of said chamber to permit escape of unsolidified gas remaining in said chamber during the compressing of the accumulated solid.

7. Apparatus of the character described, including a chamber having a closed end and a normally open end, said chamber having the wall thereof tapered whereby the chamber is smaller at the closed end than at the normally open end thereof, means for supplying a volatile

fluid to the chamber for expansion therein to afford an accumulation of solid in the chamber, a piston movable through said chamber from the normally open end thereof toward the closed end of the same to compress the solid accumulated in the chamber at the smaller end thereof, said piston being spaced from the wall of said chamber to permit escape of unsolidified gas remaining in said chamber during the compressing of the accumulated solid, closing means cooperating with the piston to close the normally open end of said chamber during the accumulation of the solid in the chamber, and means for releasably latching the closing means to the piston, said latching means releasing said closing means from the piston upon movement of the piston toward the closed end of said chamber to thereby unseal the normally open end of said chamber during the compressing of the accumulated solid.

8. Apparatus of the character described, including a chamber having a normally open end, means for supplying a volatile fluid to the chamber for expansion therein to afford an accumulation of solid in the chamber, normally closed valve means through which unsolidified gas may pass from said chamber, movable means for closing the normally open end of said chamber and for compressing the solid accumulated in the chamber into a compact form, means for operating said movable means to close the normally open end of said chamber during accumulation of the solid in said chamber and to subsequently unseal the normally open end of said chamber and compress the accumulated solid, the unsealing of the normally open end of said chamber permitting any unsolidified gas remaining in the chamber to pass therefrom through said normally open end during the compressing of the accumulated solid, and means controlled by said movable means for opening said valve during the accumulation of the solid in said chamber, the means controlled by said movable means permitting said valve to close upon the unsealing of the normally open end of said chamber.

9. Apparatus of the character described, including a chamber, means for supplying a volatile fluid to said chamber for expansion therein to afford an accumulation of solid in the chamber, means for compressing the solid accumulated in the chamber at one end of said chamber, and means at said end of said chamber connected to a source of fluid under pressure and through which pressure may be applied on the compressed solid in said chamber to effect removal of the compressed solid from the said chamber.

10. Apparatus of the character described, including a chamber, said chamber being smaller at one end than at the other end thereof, means for supplying a volatile fluid to the chamber for expansion therein to afford an accumulation of solid in the chamber, means for compressing the accumulated solid at the smaller end of the chamber, and means at the smaller end of the chamber connected to a source of fluid under pressure and through which pressure may be applied on the compressed solid in said chamber to effect removal of the compressed solid from the larger end of said chamber.
